ABSTRACT

A hull of two water-tight compartments or sections variably disposable is disclosed whereby a vessel constructed from such hull may be provided with catamaran-like characteristics as well as conventional hull-type characteristics.

FIG. 1

FIG. 2

FIG. 3

FIG. 4

FIG. 5

FIG. 6

FIG. 7

BOAT HULL CONSTRUCTION

This invention relates to a boat and more particularly to a boat with a longitudinally partitioned and variably disposable hull.

Boats of various hull configuration, shapes and designs are known, some more common, some less familiar. Each has its own characteristic which gives it certain advantages or disadvantages.

The objects of the present invention are to provide a split or sectional hull construction for a vessel to give various running characteristics as may be desired. The split hull of two watertight compartments may be constrained in juxtaposition wherein the hull proves floating characteristics of a more conventional hulled vessel. Alternatively, the compartments may be separated whereupon the hull splits to essentially form pontoons of a catamaran-like vessel and displays corresponding floating characteristics. By varying the relative position of each of the compartments, a range of operational characteristics may be achieved.

The invention therefore achieves a boat comprising: a hull of two juxtaposed hollow sections, each section including a plate and an enclosing body portion, the plate being essentially flat and longitudinally extending as a side of the section across the body portion to form a hollow member or section therewith,

b struts inter-connectingly mounted on each of the hollow sections to dispose the plates relatively proximate and substantially parallel to each other, c gear means including connection means inter-connecting the hollow sections whereby relative movement of the gear means imparts relative movement to the hollow sections whereby the sections may be selectively disposed in adjacent juxtaposition or separated at will.

The present invention will now be described by way of example with reference to the accompanying drawings in which:

FIG. 1 is a side perspective view of the hull (closed).

FIG. 2 is a perspective of FIG. 1 with the hollow sections separated.

FIG. 3 is a rear perspective of the hull of FIG. 1.

FIG. 4 is a rear perspective view of the hull of FIG. 2, partly in section.

FIG. 5 is an exploded plan view of a gear means imparting relative position to the hollow sections.

FIG. 6 is a section along lines VI—VI of FIG. 5.

FIG. 7 is a section along lines VII—VII of FIG. 5.

Referring to FIGS. 1 through 4 a vessel or boat 10 includes generally a hull 11 of two hollow preferably watertight compartments or sections 12 and 13. The sections include a body-like portion 15, an essentially flat longitudinally extending plate 16 extending to enclose the body portion 15 into an open hollow section 12. Preferably the section 12 is closed into a water-tight compartment and in such preferred embodiment there is provided a cover 17 to seal closed the section 12 into the water-tight compartment.

The water-tight hollow section 12 is a virtual image with that of section 13, hence the extending plates 16 of each of the sections 12 and 13 are relatively disposed closer together than the corresponding body portions 15.

The sections 12 and 13 are connected together through a fore and aft arrangement 18 and 19 of a pair

26 of hollow parallel guide struts 27 and 28. Into each strut 27 and 28 respectively telescopes a joist 36 and 37 each mounted at its remote end respectively to section 12 or 13. The strut 27 and 28, in their centres provide a slot or window 20 which respectively exposes racks 34 and 33 of the joist 36 and 37 as will shortly be described. It is by relative telescoping of the joists 36 and 37 that the sections 12 and 13 are positionable in relative proximal juxtaposition (FIGS. 1 and 3) or extended apart (FIGS. 2 and 4) or any variation therebetween in a manner as will be described.

A gear means 21 is provided and includes an upper and lower thrust plate 24 and 25 mounted between the pair of parallel struts 27 and 28 both in the fore arrangement and in the aft arrangement. The drive gear 29 is mounted on a vertically disposed axis 31 carried by the thrust plates 24 and 25. The axis 31 also carries a drive gear 32 or pinion which engages racks 33 and 34. The rack 33 is mounted on the margin of one of the

20 joists, for example, 36, facing the joist 37, the other rack 34 is mounted to the margin of the joist 37 which faces the joist 36. The drive arrangement aft is connected to a similar arrangement fore as by continuous chain 41 interlocking between drive gears 29 located both fore and aft. An aperture 42 is provided through the central deck 43 (and as shown in FIG. 4) is in the fore location although it may as well be at the aft. It is through this aperture 42 that a crank 44 may be inserted to engage the axis 31 by a recessed slot 45 by rotation of the crank the hull sections 12 and 13 are disposed in open or closed arrangement in the following manner:

25 Rotation of the crank 44 causes rotation of the fore axis 31 and of the fore drive gear 29 and the interlocking or telescoping (depending upon counterclockwise or clockwise rotation of the crank) of the racks 33 and 34 and hence of the associated fore joists 36 and 37. Simultaneously, through the linkage of the continuous loop chain 41 the rotation is imparted to the aft drive gear 29 and hence the aft axis 31 and in a like manner the aft joists 36 and 37 move in unison with the fore joists. The sections 12 and 13 thus respectively moved and may be positioned as shown, for example, in FIGS. 1 and 2, or as in FIGS. 3 and 4, or at any intermediate position.

45 Now the boat 10 is further provided with a plurality of longitudinal hinged interlocking deck members 49 onto which the central fixed deck 47 is securely mounted. Along the longitudinal margin of the central deck 47 are hinges 48 to provide a hinging connection

50 with interlocking deck members 49 and 50. The members 50 are hinged at 52 to the interior longitudinal margin of the hull 15 and at 53 to the interlocking member 49. The closed configuration of the hull 11, FIGS. 1 and 3, the hinged members 49 and 50 are disposed in

55 the inverted "V" while when the boat 10 is extended to its open hull position of FIGS. 2 and 4 the members 49 and 50 are flat and contiguous with the upper surface of the central deck 49 to form an extended deck surface 50, 49, 47, 49 and 50 as clearly indicated in FIGS. 2 and 4. In this arrangement the fore and aft joists 36 and 37 support the interlocking deck members 49 and 50.

60 From the aft of the central deck 47 an upward standing transom plate 51 may be provided onto which an outboard motor may be mounted to provide propulsion for the boat.

The embodiments of the invention in which an exclusive property or privilege is claimed are defined as fol-

lows:

1. A boat comprising:
  - a. a hull of two juxtaposed hollow sections, each section including a plate and an enclosing body portion, the plate being essentially flat and longitudinally extending as a side of the section across the body portion to form a hollow member or section therewith;
  - b. struts interconnectingly mounted fore and aft on each of the hollow sections and essentially at right angles to the plates to dispose the plates relatively proximate and substantially parallel to each other; and
  - c. gear means including interconnected fore and aft arrangements of a hollow parallel guide into which a strut from each hollow section telescopingly is adapted to move and means for relatively moving and constraining the struts within the guides comprising a fore and aft gear box mounted on the guides and containing a pinion gear, each strut disposing a rack along one margin which engages the pinion gear, and link means for connecting the fore and aft gear boxes whereby rotation of one pinion gear transmits rotation to the other pinion gear and relative movement of the fore and aft struts and hollow sections whereby the sections may be selectively disposed in adjacent juxtaposition or separated at will.

2. A boat comprising:

- a. a hull of two juxtaposed hollow sections, each section including a plate and an enclosing body portion, the plate being essentially flat and longitudinally extending as a side of the section across the body portion to form a hollow member or section therewith;
- b. struts interconnectingly mounted on each of the hollow sections to dispose the plates relatively proximate and substantially parallel to each other;
- c. gear means including connection means interconnecting the hollow sections whereby relative movement of the gear means imparts relative movement to the hollow sections whereby the sections may be selectively disposed in adjacent juxtaposition or separated at will; and
- d. a central rigid deck portion mounted over the struts, a pair of interfolding deck members hingably mounted between longitudinal margins of the rigid deck portion and the margin of each hollow section, whereby, when the hollow sections are disposed to their fullest extent, the interfolding deck members extend into the same plane as the rigid deck portion to form a deck, and when the hollow sections are in juxtaposition the interfolding deck members are disposed essentially vertically and surmounting the margins of the hollow section.
